ATION OF ILLINOIS.

HAIR-WAVING DEVICE.

Application filed August 13, 1926. Serial No. 128,934.

This invention relates to hair curling or waving devices; the principal object being to produce a simple and efficient article whereby the user may give to the hair a peculiar complex wave commonly known as a Marcel wave. 5

The manner of use and the various advantages of our invention will be obvious as we proceed. The invention consists in the novel 10 device and combinations of features thereof, illustrated and described, and will be more fully set forth in the claims hereunto appended.

In the accompanying drawings: 15 Figure 1 is a side view of a hair waver embodying our invention, the parts being in the open position, ready for use.

Figure 2 is a side view of the same, the 20 parts being in the closed position.

Figure 3 is a central, longitudinal section 25 view of the top member, with the lower member in side elevation, the parts being closed and in locked relation.

Figure 4 is a top or plan view of the 30 device, the parts being in the closed and locked position.

Figure 5 is a transverse, sectional view, 35 the section being taken in the vertical plane indicated by the line 5—5 on Figure 3.

Figure 6 is a transverse, sectional view, 40 the section being taken in the vertical plane indicated by the line 6—6 on Figure 2.

Figure 7 is a fragmentary, perspective 45 view illustrating the conformation of a strand of hair after our improved wavers have been applied, the dotted lines indicating the wavers in position.

Figure 8 is a fragmentary view, in side elevation, illustrating a modification.

Referring to said drawings, it will be observed that the waver, indicated as a whole by the letter A, comprises two main members, an upper member B and a lower member C. 50

The member B is bent or formed in arcuate shape longitudinally, as shown in Figures 1, 2 and 3, while in cross section it has the appearance of the letter U inverted, as shown in Figures 5 and 6. That is to say, the member B has two side members 1, 1, parallel and spaced apart as shown, which are joined by the curved, intermediate portion 2. Each side member 1 is provided on its lower edge,

intermediate its ends 3 and 4, with comb teeth 5. 55

The lower member C is a relatively thin strip of complementary arcuate form longitudinally and, when the waver A is in the closed position shown in Figures 3 and 4 the lower member C will lie between the 60 sides 1, 1, of the member B.

The members B and C are pivotally united as follows: A pivot pin 6 is passed through suitable apertures in the end portion 4 of each side 1 and through the curved, elongated slot 7 in the end 8 of the member C, as well as through washers 9, one on each side of the end 8. The end portion 3 of the member B is provided with a locking pin 10 which extends through both sides 1 as shown 70 in Figure 5.

The right hand end of the member B is slightly recessed by cutting away the intermediate member 2, the recess forming a shoulder 11 adapted to engage the shouldered 75 notch 12 in the member C when the waver is in the open position illustrated in Figure 1. The top and bottom margins of the unslotted end of the member C converge to form a blunt point 13 and the width of the 80 member C at the pointed end is such as to permit it to rest upon the locking pin 10 and below the curved part 2 of the member B when the device is closed. When the device A is thus closed, sufficient space for the hair 85 is afforded between the members B and C as indicated by 14 on Figures 3, 5 and 6.

The top, arcuate margin of the member C is provided, intermediate the pointed and slotted ends, with comb teeth 15. The shape 90 of the teeth 5 and 15 may be varied as desired,—one such variation being shown at 16 in Figure 8.

In use, the operator will open the waver A into the position shown in Figure 1, insert the member C into operative engagement with the strands of hair to be waved and then, before attempting to bring the members B and C together, move the member C longitudinally with respect to the member B 100 and until the forward end of the slot 7 engages the pivot pin 6, then swing the member G about said pivot pin 6 and into position within the member B, thus crimping the engaged strands of hair into the space 14 105 within the member B, and finally shifting

the member C longitudinally in the opposite direction, until the pointed or forward end 13 of member C will be locked in member B because resting above the locking pin 10, as shown in Figures 3, 4 and 5.

5 The strands of hair caught by the member C and pressed up into the member B are of course undulated and are thus waved. The moving of these strands forwardly towards the locking pin 10 as the member C is moved, produces that peculiar complex wave characterized by having the individual strands of hair waved in planes at an angle to the general plane of the lock of hair in 10 which said strands are associated, thereby producing what is recognized and known as a Marcel wave.

15 The device A is made of celluloid or other suitable material, is efficient and durable, does not easily get out of order, is susceptible 20 of being fabricated by easy mechanical operations and therefore made cheaply and is very neat in appearance.

25 We claim as our invention:

1. The improved hair waver comprising upper and lower inter-fitting members, pivotally united at one end, and between which members the strands of a lock of hair are transversely held to form a wave, and means 30 for shifting the lower member longitudinally within the upper member to lock the two members together and simultaneously shift the angle of the held hair strands, the lower margins of the upper member and the upper 35 margin of the lower member being provided with comb-like teeth.

2. The improved hair waver comprising an upper longitudinally curved, arcuate member having parallel, spaced apart sides and 40 an integral, curved, intermediate part, a pivot pin uniting the sides at one end of said member, a locking pin connecting the other ends of said sides, and comb-like teeth

formed on the arcuate edge of the two spaced apart sides, a second arcuate shaped member 45 provided with comb-like teeth on its upper arcuate edge and provided at one end with an arcuate elongated slot through which the pivot pin extends, the slot being so located that when its forward end is in contact with the pivot pin, the lower member 50 is not in contact with the lock pin and may swing about said pivot into and out of operative relation with the upper member, and when the rear end of the slot is in contact 55 with said pivot pin, the lower member is in operative relation with the lock pin and may not swing about the pivot pin.

3. In a hair waver, an upper member of celluloid, bent longitudinally into arcuate 60 form and having a rounded intermediate part and two integral sides, parallel and spaced apart, and provided with comb-like teeth on the curved lower margins of said sides, and a lower member, relatively thin, 65 arcuate shaped longitudinally, having a blunt point at one end and a slotted part at the opposite end, comb-like teeth on the upper margin between the two ends, and means for pivotally uniting the upper and lower 70 members, comprising a pivot pin passing through the sides of the upper member near one end thereof and through the slotted end of the lower member, said slot being elongated and arcuate, and means for holding 75 the two members in open position, consisting of a shoulder-notch in the upper edge of the lower member adapted to engage the pivot-pin end of the intermediate curved part of the upper member.

80 In testimony, that we claim the foregoing as our invention we affix our signatures, this 11th day of August, 1926.

KARL EKLUND.
MYRTLE A. LOECK.
